US00D570284S

(12) **United States Design Patent** (10) Patent No.: **US D570,284 S**
(45) Date of Patent: ** Jun. 3, 2008

(54) **CHIP-TYPE SOLID STATE ELECTROLYTIC CAPACITOR**

(75) Inventors: **Katsuhiko Yoshida**, Sendai (JP); **Koji Sakata**, Sendai (JP); **Kazuyuki Katoh**, Sendai (JP)

(73) Assignee: **NEC Tokin Corporation**, Sendai-shi (JP)

(**) Term: **14 Years**

(21) Appl. No.: **29/278,667**

(22) Filed: **Apr. 5, 2007**

(30) **Foreign Application Priority Data**

Oct. 6, 2006 (JP) 2006-027117

(51) **LOC (8) Cl.** 13-03

(52) **U.S. Cl.** D13/125

(58) **Field of Classification Search** D13/118, D13/123-125, 133, 184, 199; 320/2; 361/523, 361/535, 536, 538, 539, 540, 271, 277, 301.1, 361/328-330, 763; 429/178

See application file for complete search history.

(57) **CLAIM**

The ornamental design for a chip-type solid state electrolytic capacitor, as shown and described.

DESCRIPTION

FIG. 1 is a front, bottom and right side perspective view of a chip-type solid state electrolytic capacitor showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
